CLAIM

The ornamental design for a mini exercise cycle for losing weight, as shown and described.

DESCRIPTION

FIG. 1 is a perspective view of a mini exercise cycle for losing weight showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a perspective view similar to FIG. 1, with the handlebar and seat in a raised position.
